The ornamental design for an LED subassembly for light bulb, as shown and described.

DESCRIPTION

FIG. 1 is a perspective of a first embodiment of the LED subassembly for light bulb having 5-sides with one LED on each side and one LED on top (6 LEDs total);

FIG. 2 is a rear elevation thereof;

FIG. 3 is an elevation showing the left side thereof;

FIG. 4 is an elevation showing the right side thereof;

FIG. 5 is a front elevation thereof;

FIG. 6 is a top plan thereof;

FIG. 7 is a bottom plan thereof;

FIG. 8 is a perspective of a second embodiment of the LED subassembly for light bulb having 4-sides with one LED on each side and one LED on top (5 LEDs total);

FIG. 9 is a rear elevation of the second embodiment;

FIG. 10 is an elevation showing the left side of the second embodiment;

FIG. 11 is an elevation showing the right side of the second embodiment;

FIG. 12 is a front elevation of the second embodiment;

FIG. 13 is a top plan of the second embodiment;

FIG. 14 is a bottom plan of the second embodiment;

FIG. 15 is a perspective of a third embodiment of the LED subassembly for light bulb having 3-sides with one LED on each side and one LED on top (4 LEDs total);

FIG. 16 is a rear elevation of the third embodiment;

FIG. 17 is an elevation showing the left side of the third embodiment;

FIG. 18 is an elevation showing the right side of the third embodiment;

FIG. 19 is a front elevation of the third embodiment;

FIG. 20 is a top plan of the third embodiment; and FIG. 21 is a bottom plan of the third embodiment. FIG. 22 is a perspective of a fourth embodiment of the LED subassembly for light bulb having 2-sides with one LED on each side (2 LEDs total); FIG. 23 is a rear elevation of the fourth embodiment; FIG. 24 is an elevation showing the left side of the fourth embodiment; FIG. 25 is an elevation showing the right side of the fourth embodiment; FIG. 26 is a front elevation of the fourth embodiment; FIG. 27 is a top plan of the fourth embodiment; and FIG. 28 is a bottom plan of the fourth embodiment. FIG. 29 is a perspective of a fifth embodiment of the LED subassembly for light bulb having 5-sides with two LEDs on each side and one LED on top (11 LEDs total); FIG. 30 is a rear elevation of the fifth embodiment; FIG. 31 is an elevation showing the left side of the fifth embodiment; FIG. 32 is an elevation showing the right side of the fifth embodiment; FIG. 33 is a front elevation of the fifth embodiment; FIG. 34 is a top plan of the fifth embodiment; and FIG. 35 is a bottom plan of the fifth embodiment. FIG. 36 is a perspective of a sixth embodiment of the LED subassembly for light bulb having 4-sides with two LEDs on each side and one LED on top (9 LEDs total); FIG. 37 is a rear elevation of the sixth embodiment; FIG. 38 is an elevation showing the left side of the sixth embodiment; FIG. 39 is an elevation showing the right side of the sixth embodiment;

FIG. 40 is a front elevation of the sixth embodiment; FIG. 41 is a top plan of the sixth embodiment; and FIG. 42 is a bottom plan of the sixth embodiment. FIG. 43 is a perspective of a seventh embodiment of the LED subassembly for light bulb having 3-sides with two LEDs on each side and one LED on top (7 LEDs total); FIG. 44 is a rear elevation of the seventh embodiment; FIG. 45 is an elevation showing the left side of the seventh embodiment; FIG. 46 is an elevation showing the right side of the seventh embodiment; FIG. 47 is a front elevation of the seventh embodiment; FIG. 48 is a top plan of the seventh embodiment; and FIG. 49 is a bottom plan of the seventh embodiment. FIG. 50 is a perspective of a eighth embodiment of the LED subassembly for light bulb having 2 sides with two LEDs on each side (4 LEDs total); FIG. 51 is a rear elevation of the eighth embodiment; FIG. 52 is an elevation showing the left side of the eighth embodiment; FIG. 53 is an elevation showing the right side of the eighth embodiment; FIG. 54 is a front elevation of the eighth embodiment; FIG. 55 is a top plan of the eighth embodiment; and, FIG. 56 is a bottom plan of the eighth embodiment. The broken lines shown in the drawings indicate structure and features which form no part of the claimed design. The glass bulb illustrated in broken lines can be transparent, translucent, frosted, clear, white and/or colored.
